United States Patent Office

Des. 224,871
Patented Oct. 3, 1972

224,871

COMMODE

Thomas Winrow, Naperville, Ill., assignor to Futorian Corporation, Amsterdam, N.Y.

Filed Dec. 7, 1970, Ser. No. 26,320

Term of patent 14 years

Int. Cl. D6—04

U.S. Cl. D6—165

The figure is a perspective view of a commode illustrating my new design. The back and the side not shown are substantially identical to the side shown.

I claim:

The ornamental design for a commode, substantially as shown and described.
